UNITED STATES PATENT OFFICE.

LLOYD S. COONEY, OF PORT CHESTER, NEW YORK, ASSIGNOR TO ABENDROTH BROTHERS, OF PORT CHESTER, NEW YORK, A CORPORATION OF NEW YORK.

DESIGN FOR A TOP GRATE FOR STOVES.

Application filed June 6, 1925. Serial No. 13,694. Term of patent 7 years.

To all whom it may concern:

Be it known that I, LLOYD S. COONEY, a citizen of the United States, residing at Port Chester, in the county of Westchester and State of New York, have invented a new, original, and ornamental Design for Top Grate for Stoves, of which the following is a specification, reference being had to the accompanying drawings, forming part thereof.

In the drawings:

Figure 1 is a top plan view of the grate.

Figure 2 is a bottom plan view of the grate.

Figure 3 is a sectional view of the grate.

I claim:

The ornamental design for a top grate for stoves as shown.

LLOYD S. COONEY.
